UNITED STATES PATENT OFFICE.

HERBERT H. DOW, OF MIDLAND, MICHIGAN, ASSIGNOR TO THE DOW CHEMICAL COMPANY, OF MIDLAND, MICHIGAN, A CORPORATION OF MICHIGAN.

ELECTRICAL APPARATUS.

Application filed January 5, 1927, Serial No. 159,084. Renewed November 17, 1927.

This invention relates to electrical apparatus, and more particularly apparatus in which conductors are immersed in a dielectric liquid. In transformers for instance, it is customary to set the core and windings in a casing and fill the space therebetween with oil. The mineral oils used however form sludges which introduce difficulties in transformer maintenance. An apparatus equipment employing a more advantageous dielectric is accordingly highly desirable.

To the accomplishment of the foregoing and related ends, the invention, then, consists of the features hereinafter fully disclosed, and particularly pointed out in the claims, the following description and the annexed drawing setting forth in detail but one of the various ways in which the principle of the invention may be employed.

In said annexed drawing, the sole figure is a vertical sectional view of a construction embodying the invention.

The casing 1, ordinarily with ribbed or corrugated wall contour to present a maximum of radiating surface, contains the transformer windings 2 and core 3. The detail of the core, and the bushings and leads through the case, and the details of the windings may be varied as individual requirements dictate, but between the casing and windings there is provided a dielectric liquid comprising a stable aryl or aromatic organic compound. Diphenyl oxide, for example, while presenting excellent characteristics in a dielectric sense and also as a heat transfer medium, of itself has a freezing point or temperature of solidification of about 27° C., which is such as to be disadvantageous in cold climate usage. By modifying the diphenyl oxide with an agent for lowering the freezing point, the desirable properties are retained while at the same time a range of availability adaptable to cold climate usage is had. As such agents, I have found that chlorinated hydrocarbons, particularly carbon tetrachloride, are effective and advantageous. From 10 to 30% of carbon tetrachloride for instance may be used, and the freezing point can be regulated as desired. A composition of diphenyl oxide 70% and carbon tetrachloride 20% shows initial crystal formation at a temperature of 16° C. The crystals formed float freely in the menstruum of remaining liquid, and it is only as the temperature is reduced further to -2° C. that solidification occurs. Diphenyl

oxide for instance, on melting expands considerably, and as a safeguard in the event that the transformer be subjected to very low temperatures with the current off, and the dielectric liquid should solidify entirely, I provide for melting at the surface first as the current is put on. Pressure from internal melting under a hard crust is thus avoided and, consequently, no damage to case or windings can result. For such surface melting, I arrange a portion of the transformer that will heat up quickly, as a projection near or through the surface of the dielectric, either as a special projection or a portion of the core as such, or an additional resistance heater. In this manner, when the current is put on, the heating projection will melt the surface of the dielectric first and there is no opportunity for internal pressure with any dielectric filler that may be used having such tendency to expand when melted.

Other modes of applying the principle of the invention may be employed, change being made as regards the details disclosed, provided the means stated in any of the following claims, or the equivalent of such, be employed.

I therefore particularly point out and distinctly claim as my invention:

1. In apparatus of the character described, the combination of a casing, transformer windings and core, and a dielectric liquid between said casing and windings, said liquid comprising an aryl compound and an agent for lowering the freezing point.

2. In apparatus of the character described, the combination of a casing, transformer windings and core, and a dielectric liquid between said casing and windings comprising an aryl compound and an agent for lowering the freezing point, a projection of said core extending in the region of the surface of said liquid.

3. In apparatus of the character described, the combination of a casing, transformer windings and core, and a dielectric liquid between said casing and windings, said liquid comprising diphenyl oxide and an agent for lowering the freezing point.

4. In apparatus of the character described, the combination of a casing and conductors therewithin, a dielectric liquid between said casing and conductors, and means for melting the surface portion of the dielectric prior to the deeper portion, after freezing.

5. In apparatus of the character described, the combination of a casing and transformer windings and core, and a dielectric liquid between said casing and windings comprising diphenyl oxide and an agent for lowering the freezing point, a projection of said core extending out of said liquid.
6. In apparatus of the character described, the combination of a casing, transformer windings and core, and a dielectric liquid between said casing and windings, said liquid comprising diphenyl oxide and carbon tetrachloride.
7. In apparatus of the character described, the combination of a casing, transformer windings and core, and a dielectric liquid between said casing and windings comprising diphenyl oxide and carbon tetrachloride, a projection of said core extending out of said liquid.
8. In electrical apparatus, the combination of a normally liquid dielectric comprising an aryl compound and a smaller proportion of an agent operating against freezing thereof as a coherent mass, and electric conductors therein.
9. In electrical apparatus, the combination of a normally liquid dielectric comprising diphenyl oxide and a smaller proportion of an agent operating against freezing thereof as a coherent mass, and electric conductors therein.
10. In electrical apparatus, the combination of a normally liquid dielectric comprising an aryl compound and an organic chlor compound, and electric conductors therein.
11. In electrical apparatus, the combination of a normally liquid dielectric comprising diphenyl oxide and an organic chlor compound, and electric conductors therein.

Signed by me this 24th day of December, 1926.

HERBERT H. DOW.
